(57) **CLAIM**

The ornamental design for the notebook computer with rotatable screen, as shown and described.

DESCRIPTION

FIG. 1 is a top, front, and right perspective view of a notebook computer with a rotatable screen in an open and rotated state showing our new design;

FIG. 2 is a front side view thereof;

FIG. 3 is a rear side view thereof;

FIG. 4 is a left side view thereof, wherein the bottom edge of the rotatable screen and the top surface of the notebook host constitute a V-shaped angle to avoid scratching the top surface of the notebook host while rotating the rotatable screen;

FIG. 5 is a right side view thereof;

FIG. 6 is a top plan view thereof;

FIG. 7 is a bottom plan view thereof; and,

FIG. 8 is a right side view thereof, wherein the bottom edge of the rotatable screen and the top surface of the notebook host constitute a V-shaped angle θ which is initially over the horizontal line;

All of the features shown in broken lines are unclaimed.
